Opposite page 12 of this volume appears a detailed
map of the area around the site of the ancient fortification
of Gath. The map is based on the results of the excavations
of the site, and shows the various structures and features
discovered. The map is accompanied by a brief description
of the site and its history, and by a list of the publications
which have been written on the subject. The map is
reproduced from the original drawing, and is printed in
black and white. The title of the map is "Map of the
Site of the Ancient Fortification of Gath".

UNITED STATES PATENT OFFICE

2,517,156

EVAPORATIVE COOLER

Bruno J. Zapart, Chicago, Ill., and Rudolph A. Mack, Phoenix, Ariz.

Application August 24, 1945, Serial No. 612,426

6 Claims. (CL 62—1)

Application August 24, 1945, Serial No. 612,426

1. *What is the relationship between the two main characters?*

6 Claims. (CL 62—1)

The present invention relates to refrigerating devices and has for its main object the provision of a suitable mechanism for using a suitable refrigerant, such as gasoline, and set between the source of gasoline, such as automobile gasoline tank, and the point of its ultimate consumption, such as automobile engine, thereby eliminating usual condensers, electric motors, etc.

A still further object of the invention is the provision of a refrigerating device of the character indicated, which may have comparatively few parts, without detracting from the efficiency of its operation.

A still further object of the present invention is to improve and simplify the construction of the refrigerating devices of the character above indicated.

With the above general objects in view and others that will appear as the invention is better understood, the same consists in the novel construction, combination and arrangement of parts hereinafter more fully described, illustrated in the accompanying drawing and pointed out in the appended claims.

In the drawing forming a part of this application, the figure is a side view, partly in section of the present device on a vertical plane, diagrammatically showing its relative position with respect to a motor vehicle gasoline tank and an engine.

Referring in detail to the present drawing there is shown a motor vehicle gasoline tank 1, with the bottom of which pipe 2 connects. Said pipe 2 passes through the bottom of tank 3, and within a suitable distance from the bottom of said latter tank connects with float valve 4 which is actuated by float 5, the latter floating upon the surface of gasoline 6 within said tank 3. Gasoline is fed into tank 3 by means of said pipe 2 and valve 4.

into tank 3 by means of said pipe 2 and valve 4. Connecting with the bottom of tank 3 is vertical pipe 7, having at its lower end elbow 8 which merges with the lower end portion of coil pipe 9. The bottom end of said coil pipe 9 is gradually rising forming an incline, its lowermost point being adjacent to said vertical pipe 7, for the purpose presently described.

purpose previously described. Entering into the bottom end of said coil pipe 9 through said elbow 8 is an air eduction pipe 10, the opposite end of said pipe 10 being provided with bleeder valve 11. Said bleeder valve 11 may be suitably adjusted for regulating the amount of air to be passed through pipe 10 and therefrom injected into the lower end of pipe 9. Since the lower end of coil pipe 9 is at an incline the air injected therewith rises upwardly through

said coil pipe 9 and does not pass into said vertical pipe 7.

The upper end of coil pipe 9 connects with the bottom of surge tank 12, into which gasoline and mixture of air and gasoline gases pass from said coil pipe 9.

10 Connecting with the upper end of surge tank 12 is pipe 13. The latter pipe connects with check valve 14. Connecting with check valve 14 is pipe 15, the latter leading into and connecting with manifold 16, and intermediately of carburetor 17 and engine 18. Through pipe 19, the latter connecting with tank 1 and carburetor 17, gasoline is fed into carburetor 17. Mixture of air and 15 gasoline vapors passes from carburetor 17 through manifold 16 into engine 18, where it is used up as a motive power for a motor vehicle in the usual manner.

Tank 3 and surge tank 12 are substantially positioned upon the same horizontal plane, their upper ends being connected by a by-passing pipe 22.

The upper end of tank 3 is provided with lid 21, on removal of which access may be had into tank 3 for cleaning, etc.

25 tank 3 for regulating float valve 4. Coil pipe 9 and surge tank 12 are enclosed within housing 22 in which suitable openings may be provided through which cooled air may normally pass to the outside of said housing 22 for 30 cooling the interior of a motor vehicle, or through which the same may be blown out by suitable blowers. If the device is used at home as a refrigerator, housing 22 may be the walls of a refrigerating unit.

35 The bottom of said housing 22 is provided with reservoir 23 into which water may precipitate when the ice clinging to coil pipe 9 melts, on defrosting of the device. Through check valve 24 connecting with reservoir 23 the water may pass
40 outwardly.

As to the operation of the device it is noted that vacuum is maintained in manifold 16 and pipe 15 due to the suction exerted upon the contents thereof by engine 18. Gasoline passes into tank 3 through pipe 2 and float valve 4 from tank 1. From said tank 3 gasoline passes through pipe 7 into coil pipe 9, filling the latter. Air passing through bleeder valve 11 and pipe 10 is injected into coil pipe 9 and mixes there with the gasoline causing vaporization thereof under the influence of vacuum maintained in surge tank 12 and pipe 13. The degree of vacuum maintained in surge tank 12 and pipe 13 is sufficient to act upon bleeder valve 11 to suck such an amount of air through pipe 10 as may be required to mix

with the gasoline in coil pipe 9 to effect proper mixing thereof with the gasoline and proper vaporization of the latter under the vacuum induced by engine 18 in said surge tank 12 and pipe 13 through check valve 14.

If tank 3 were to be completely sealed from surge tank 12, the required amount of gasoline could not possibly pass into said tank through float valve 4 due to the seal of gasoline in coil pipe 9. The by-passing pipe 20 connecting with said tank 3 and surge tank 12 equalizes the pressure in the two permitting normal flow of gasoline into said tank 3 through said float valve 4.

Said by-passing pipe 20 also permits maintenance of gasoline in tank 3 and surge tank 12 at the same level as is shown in full lines in said tank 3 and by dotted line in said surge tank 12.

The gasoline in coil pipe 9 and in surge tank 12, of course gradually is consumed due to its vaporization and ultimate consumption by engine 18 as it passes thereinto from surge tank 12 through pipes 13 and 15 and manifold 16 and check valve 14, when in the form of air and gasoline vapor mixture. This consumption of gasoline lowers the level of the gasoline within tank 3, thereby causing float 5 to shift downwardly. As the gasoline in coil pipe 9 and surge tank 12, as well as in tank 3 is periodically consumed, and its level in tank 3 is periodically lowered, and thereby float 5 is periodically shifted downwardly, float valve 4 is periodically opened for the purpose of periodically adding to the amount of gasoline in tank 3 and surge tank 12 as well as in coil pipe 9.

When float 5 opens valve 4, gasoline is sucked into tank 3 through said valve 4 by virtue of vacuum in said tank 3.

From the hereinabove description it will be seen that due to constant evaporation of gasoline in coil pipe 9 extreme cold is engendered in said coil pipe 9 and outwardly thereof so that coil pipe 9 becomes frosted.

It is also observed that by providing refrigerating mechanism on the path between the source of the refrigerant, such as tank 1, and the point of its ultimate consumption, such as engine 18, the refrigerating mechanism requires no condensers or electric motors.

It is further observed that the refrigerating process takes place in coil pipe 9 and not in surge tank 12. Coil pipe 9 being of a comparatively small diameter the vacuum acts upon its contents in a greater degree to bring about vaporization of the gasoline when mixed with air, than in surge tank 12 where the air and gas mixture upon leaving coil pipe 9 expands, from where it is pumped through check valve 14 by the action of engine 18 and through pipes 13 and 15 and intake manifold 16.

Although the device would work comparatively well without check valve 14, without it however uniform degree of vacuum in surge tank 12 and pipe 13, to act upon gasoline in coil pipe 9 could not be had due to varied cycles of the operation of engine 18 and consequently due to the varied degrees of vacuum engendered thereby in pipe 15 and manifold 16. As the suction action of engine 18 is increased, gas is sucked from surge tank 12 through check valve 14. During intervals in the operation of engine 18 when the suction in pipe 15 and manifold 16 is not sufficient to overcome check valve 14 for opening the same no gas passes therethrough from surge tank 12, but nevertheless during those latter intervals there still is a sufficient degree of vacuum induced in

said surge tank 12 by prior intervals of the operation of engine 18, to efficiently act upon gasoline in coil pipe 9 to evaporate the same.

The device herein disclosed need not necessarily be limited for use in motor vehicles either passenger or trucks. The same may be employed for homes, freight cars transporting food etc. Other refrigerants such as ammonia water, may be employed. If the device is employed for home use, fuel oil may be employed as the refrigerant in connection with the device.

While there is described herein a preferred embodiment of the present invention, it is nevertheless to be understood that minor changes may be made therein without departing from the spirit and scope of the invention as claimed.

What we claim as new is:

1. A refrigerating device adapted to be operated by an internal combustion engine having suction intake means, a suction line adapted for connection with the suction means, a surface cooling element having upper outlet and lower inlet end portions with said upper end portion connected with the suction line, a supply tank, a pipe extending downwardly from the supply tank to the inlet end portion and connected therewith, said inlet end portion being inclined upwardly from said connection with the supply pipe, and an eduction tube located in said inclined tube and terminating inside the inlet end at a point away from the point of connection of the supply pipe therewith, and means for supplying a gaseous fluid to the eduction tube.

2. A refrigerating device adapted to be operated by an internal combustion engine having intake means, a suction line adapted for connection with the suction means, a surface cooling element including a coil having upper outlet and lower inlet end portions with said upper end portion connected with the suction line, a supply tank, a pipe extending downwardly from the supply tank to the inlet end portion and connected therewith, said coil being substantially in helical form about an upwardly extending axis and with said inlet end portion upwardly inclined from the point of connection with the supply pipe, an eduction tube of lesser diameter than the coil and in said coil extending into the inlet end portion of the coil and terminating at a point spaced from the point of connection with the supply pipe, and means to supply air to said tube for passage of air through the coil for vaporization of a fluid therein.

3. A refrigerating device adapted to be operated by an internal combustion engine having intake means, a suction line adapted for connection with the suction means, a surface cooling element including a coil having upper outlet and lower inlet end portions with said upper end portion connected with the suction line, a supply tank, a pipe extending downwardly from the supply tank to the inlet end portion and connected therewith, said coil being substantially in helical form about an upwardly extending axis and with said inlet end portion upwardly inclined from the point of connection with the supply pipe, means for supplying air to said inlet end portion of the coil at a point spaced from the point of connection with the supply pipe for passage of air through the coil for vaporization of a fluid therein, said supply tank including means for periodically admitting fuel thereto to maintain a liquid level in said tank, a surge tank connecting the coil with the suction line, and means connecting the surge tank with the supply tank.

4. A refrigeration device comprising suction means, a heat exchange coil having upper and lower ends, a surge tank connected to the upper end of said coil, means connecting the surge tank to the suction means, a supply tank connected to the lower end of said coil, a by-pass connecting the surge tank to the supply tank, and a tube extending into the lower end of said coil, said tube being adapted for supplying air to vaporize a liquid in said coil.

5. A refrigeration device comprising suction means, a heat exchange coil having upper and lower ends, a surge tank connected to the upper end of said coil and positioned thereabove, means connecting the surge tank to the suction means, a liquid supply tank positioned above the heat exchange coil, means to maintain the liquid in said supply tank at a predetermined level, means connecting the surge tank to the supply tank, said means being located above the level of the liquid in the supply tank, an upright pipe connecting the bottom of the supply tank to the lower end of the heat exchange coil, an eduction tube extending into the lower end of the heat exchange coil and terminating within the coil at a point spaced from the lower end of said upright pipe, and means to supply air to said eduction tube for vaporizing a liquid in said heat exchange coil.

6. A refrigeration device comprising suction means, a heat exchange coil having upper and lower ends, a surge tank connected to the upper

end of said coil and positioned thereabove, means connecting the surge tank to the suction means, a check valve in the means connecting the surge tank to the suction means, a liquid supply tank positioned above the heat exchange coil, means to maintain the liquid in said supply tank at a predetermined level, means connecting the surge tank to the supply tank, said means being located above the level of the liquid in the supply tank, a vertical pipe connecting the bottom of the supply tank to the lower end of the heat exchange coil, an eduction tube extending into the lower end of the heat exchange coil and terminating within the coil at a point spaced from the lower end of said vertical pipe, and means to supply air to said eduction tube for vaporizing a liquid in said heat exchange coil.
